TRANSFER APPARATUS

Ralph E. Cross, Grosse Pointe, Mich.

Application July 25, 1947, Serial No. 763,531

3 Claims. (Cl. 198—218)

1

This invention relates broadly to transfer apparatus and more particularly to apparatus of this character which is adapted to transfer workpieces progressively through a series of work stations.

An important object of the present invention is to provide an apparatus which will pick up a workpiece from one work station, transfer it laterally to an adjacent station, deposit it, and then return to the first station.

Another object of the invention is to provide an apparatus of the above-mentioned character which can be easily adapted to handle many types of work.

Still another object of the invention is to provide an apparatus of the above-mentioned character having means for automatically positioning workpieces properly with respect to a work station adjacent thereto.

Yet another object of the invention is to provide an apparatus of the above-mentioned character which is automatic in operation.

A further object of the invention is to provide an apparatus of the above-mentioned character which can be readily controlled by mechanism in the work station to cycle automatically as soon as the operation to be performed in that particular station is completed.

A still further object of the invention is to provide an apparatus of the above-mentioned character having means for positioning the workpiece during that portion of the cycle when it is transferred from one work station to another.

A yet further object of the invention is to provide an apparatus of the above-mentioned character which is simple but rugged in construction and relatively inexpensive to manufacture.

Other objects and advantages of the invention will be apparent during the course of the following description.

In the drawings forming a part of this specification and wherein like numerals are employed to designate like parts throughout the same:

Fig. 1 is a top plan view of a transfer apparatus embodying one form of the invention;

Fig. 2 is a vertical sectional view taken on the line 2—2 of Fig. 1;

Fig. 20 is a schematic view of the control system for the modified transfer apparatus.

Considered in certain of its broader aspects, the invention comprises an apparatus for moving workpieces automatically from one work station to another and progressively through a series of work stations. The work stations must be uniformly spaced and usually are occupied by machines which perform some operation on the work; however, the stations may merely contain supports which hold idle workpieces between machining operations or they may contain apparatus for positioning the work properly with respect to a machine in the next succeeding station.

In general, the apparatus comprises stationary work supports in each work station, transfer devices having a horizontally movable slide equipped with work-holding members, and hoists for raising and lowering the slide to move the work-holding members between positions above and below the stationary work supports. Means is provided for shifting the slide horizontally and

55

for properly controlling the movements both of the slide and of the hoists. By properly co-ordinating the movements of the various mechanisms, the apparatus can be made to cycle automatically either continuously or intermittently under the control of a manual starter switch.

At the beginning of a cycle, the apparatus is positioned with the hoists lowered, the slide retracted, and the work-holding members positioned to engage workpieces on the stationary work supports. In operation, the slide is first raised by the hoists to lift the work-holding members from a position below to a position above the stationary work supports so that the members pick up workpieces from the supports. The slide is then moved horizontally in the manner hereinabove described to transfer the workpieces to adjacent work stations, and the hoists are then lowered to deposit the workpieces on the stationary supports in the last-mentioned stations. To complete the cycle of operation, the slide is returned either with the hoist in lowered position or the motions hereinabove described are reversed with the work-holding members positioned to release or disengage the workpieces depending upon exigencies of the particular situation. The above steps are performed simultaneously in all of the work stations, and after each cycle of operation, an unfinished workpiece is placed either manually or by suitable mechanical means on the first station at one end of the apparatus, and a finished workpiece is removed from the last station at the opposite end thereof.

The apparatus shown in Figs. 1-9 was designed primarily for transferring pipe or the like; however, it is not intended that the apparatus be limited to this use, as it may be employed in any capacity where an apparatus of this character has utility. In the apparatus here shown by way of illustration only four work stations designated generally by the numerals 20, 22, 24, and 26 are shown, but it will be readily apparent that the apparatus can be easily adapted to operate with any desired number of stations. Also, it will be observed that in the illustration all four stations are at one side of the transfer device. This arrangement, however, is not essential, since if desired, certain of the work stations may be at one side of the transfer device and other work stations at the other side thereof.

Work stations 22 and 26 are occupied by machines for performing certain operations on the workpieces, work station 20 contains apparatus for positioning the work properly with respect to the machines in station 22, and work station 24 is merely an intermediate idle station in which no operations are performed on the work. The specific construction and operation of machines in stations 22 and 26 are conventional and comprise no part of the present invention. They are shown merely by way of illustration, and since they are incidental to the invention a detailed description thereof is not necessary.

The apparatus here shown is adapted to transfer two workpieces side by side simultaneously through work stations 20, 22, 24, and 26. In this connection, however, it will be readily apparent that the apparatus can be readily adapted to handle a single workpiece in each work station or to handle three or more workpieces simultaneously in each work station.

The first work station 20 comprises a series of rollers 28 which support the workpieces (not shown) and a vertical stop 30 at one end of the

rollers 28. In operation, the stop 30 abuts one end of the workpieces and positions the latter properly with respect to the machines in adjacent work station 22. As best shown in Fig. 1, the rollers 28 are arranged in pairs and the two rollers in each pair are fixed on a shaft 32, which shaft is supported at its ends by standards 34 (Fig. 5) and is continuously driven by a motor 36 through gears 38 and 40 and an endless chain 42. Corresponding rollers 28 in each pair are disposed in alignment with each other, so that a pipe or other workpiece of elongated structure can be laid thereon and collectively supported thereby.

Thus, in the work station 20 here shown, two pipes are placed side by side on the two series of rollers 28, and motors 36 continuously rotate these rollers in a direction to move the workpieces axially against the stop 30. The workpieces may be loaded on the rollers 28 either manually or mechanically by apparatus well known in the art, and, in practice, they preferably are placed on the rollers in approximately the desired position with respect to the stop 30. Thus, the axial travel imparted to the workpieces by the rollers 28 is relatively short, and as a consequence, the rollers can be rotated relatively slowly. The rollers continue to rotate after the workpieces have moved against stop 30 and hold the workpieces so positioned until they are picked up by the transfer device.

The apparatus for transferring the workpieces from one work station to another comprises stationary work holders 44 and transfer devices 46 arranged alternately in laterally spaced relation at one side of the rollers 28 and extending across the entire series of work stations 20, 22, 24, and 26. In the embodiment of the invention here shown, three stationary work holders 44 are provided between four transfer devices 46. In this connection, however, it will be readily understood that the number of work holders 44 or transfer devices 46 is not critical and that any number of these units required to handle a particular workpiece can be provided. Also, in many instances it may not be necessary to provide a stationary work holder 44 between each pair of transfer devices 46. For example, if the workpieces are uniformly long and rigid, two work holders at opposite ends of the apparatus may be sufficient. On the other hand, if some of the workpieces are relatively short or are flexible in character, it may be necessary to provide more than one stationary work holder 44 between each pair of adjacent transfer devices 46.

For a specific description of the stationary work supports 44 reference is had to Fig. 6. All of the supports 44 are identical in construction, and a detailed description of one therefore will suffice.

Each support 44 comprises a horizontal beam 48 which is supported at spaced intervals by upright standards 50 and carries a plurality of uniformly spaced upstanding V-blocks 52. All of the supports 44 are of uniform height and the height is determined by the character of the machines in stations 22 and 26. In practice, the workpieces rest on the V-blocks 52 and these blocks should position the workpieces for proper engagement by the machines. Since the workpieces are supported by rollers 28 in work station 20, the supports 44 extend only across work stations 22, 24, and 26. Two V-blocks 52 are provided on each beam 48 for each of the work stations 22, 24, and 26, and the V-blocks are spaced uniformly with

respect to each other and with respect to the rollers 28.

For a detailed description of the transfer devices 46 reference is had to Figs. 2, 3, and 4. All of the transfer devices 46 are identical in construction and operation, and a detailed description of one therefore is sufficient.

Each transfer device 46 comprises a slide 54 mounted for horizontal translatory movement on a supporting beam 56. The beam 56, in turn, is carried by and supported on two hoists 58 located adjacent opposite ends thereof. Slide 54 carries a row of V-blocks 60 which are uniformly spaced on the same centers as V-blocks 52, and provision is made for driving these slides back and forth on the beam 56 a distance equal to the distance between adjacent work stations 20, 22, 24, and 26. At one end of its horizontal travel, slide 54 is positioned with the two endmost V-blocks 60 in alignment with respective rows of rollers 28, and at the other limit of its travel, the two V-blocks 60 referred to above are positioned in alignment with the two endmost V-blocks 52 on the stationary work holders 44. Hoists 58 raise and lower the slide assembly to move the V-blocks 60 between positions above and below the V-blocks 52.

At the beginning of a cycle of operation, slide 54 is retracted a maximum distance to the left as shown in Fig. 2 so that the two endmost V-blocks 60 are aligned with the two series of rollers 28 (Fig. 1), and the hoists 58 are lowered to position V-blocks 60 below rollers 28 and also below the V-blocks 52. Two workpieces are then placed on respective rollers 28 and are immediately shifted longitudinally by the latter against the stop 30, which stop positions them for proper engagement with the machine in work station 22.

As soon as the workpieces engage stop 30, the transfer device is operated to transfer them to work station 22. As the transfer device begins its cycle of operation, the hoists 38 raise the slide 54 and its supporting beam 56 sufficiently to move V-blocks 60 to a position above rollers 28. As V-blocks 60 rise to a position above the rollers 28, they pick up the workpieces and lift them sufficiently to clear the rollers. When hoists 58 reach the upper limit of their travel, the slides 54 are moved simultaneously to the right, as viewed in Fig. 2, to position the workpieces directly above the first two V-blocks 52 and in alignment with respective machines in work station 22. Hoists 58 are then moved downwardly a distance sufficient to position V-blocks 60 below V-blocks 52. Manifestly, when V-blocks 60 move below the V-blocks 52, workpieces carried thereby are deposited on the stationary work supports 48 and are entirely released by V-blocks 60. As soon as hoists 58 reach the lower limit of their travel, slides 54 traverse to the left as viewed in Fig. 2 to their initial or starting position. As suggested, two workpieces are then placed on the rollers 28 preparatory to another cycle of operation by the transfer device, while the two workpieces which were transferred to work station 22 are acted upon by the machines in the latter station.

From the foregoing, it will be readily apparent that each operation of the transfer devices 46 moves workpieces from any or all of work stations 20, 22, 24, and 26 to the next succeeding work station. The workpieces are moved in groups of two and all of the workpieces are moved simultaneously. Those workpieces removed from the endmost work station 26 are deposited on the two endmost V-blocks 52 of stationary supports 78

48 from which they are removed either manually or by suitable mechanical means before the transfer device completes another cycle of operation.

It will be readily apparent that the mechanism here shown can be adapted to any number of work stations merely by elongating the stationary supports 48 and transfer devices 46. Also, it will be readily apparent that the transfer devices 46 can be made to cycle automatically at spaced intervals by suitable timing devices or that it can be made to cycle automatically under the control of a manual starter.

Each of the transfer devices 46 here shown has the same basic structure, and for a detailed description of the same reference is had to Figs. 2-4. The slide 54 is shown in the form of an I-beam (Figs. 3 and 4), and the V-blocks 60 are welded or otherwise fastened permanently on the upper flange thereof. The support 56 comprises a pair of channels 62 arranged in parallel, spaced relation below the slide 54 and fastened solidly together by a transverse bar 64. Rollers 66 carried by and located at opposite sides of the I-beam 54 travel on wear plates 68 welded or otherwise fastened on the upper flanges of channels 62. Wear plates 68 may extend the full length of the supporting channel 62 or they may extend only for a short distance corresponding to the travel of the I-beam as shown in the drawings.

Hoists 58 are provided at opposite ends of the transfer device as perhaps best shown in Fig. 2, and since the hoists are identical, a detailed description of but one is given. Each hoist comprises a housing 70 having base flanges 72 which are anchored solidly to the floor or other suitable support by bolts 74 or the like. A pair of laterally spaced racks 76 are mounted for vertical sliding movement in the housing 70, and the upper ends 40 of the racks extend above the housing and are fastened to respective channels 62 by suitable mountings 78. The two racks 76 are raised and lowered simultaneously by pinions 80 on a shaft 82 which extends transversely through and is journaled for rotation in the housing 70. Intermediate the two pinions 80 is a driving pinion 84; and a horizontal rack 86, mounted for sliding movement in the housing 70, meshes with the pinion 84 to rotatably drive the same. In order to relieve the various racks and pinions of excessive strain, a counterweight 88 is provided for each of the vertical racks 76. In the form of the invention here shown, the counterweights 88 are disposed in suitable guides 90 on one vertical wall of the housing 70 and are connected to their respective racks 76 by flexible cables 92, which cables pass through openings 94 in the upper portion of the wall and over pulleys 96 which are journaled for rotation in the openings 94.

As best shown in Fig. 2, the two horizontal racks 86 of hoists 58 are connected for simultaneous operation by a connecting rod 98 so that all four of the vertical racks 76 operate in unison.

Provision also is made for co-ordinating the slides and hoists of the several transfer devices 46. To this end, a rack 100 is fastened to the bottom flanges of each I-beam slide 54, and these racks mesh with pinions 102 carried by a common shaft 104 which connects the transfer devices 46 and is journaled for rotation in suitable bearings 106 in channel supports 62 (Fig. 3). Thus if any slide 54 is actuated, motion is transferred to the other slides in the assembly through the shaft 104. As a result, all of the slides 54

are positively connected for simultaneous operation. Similarly, the horizontal shafts 82 of hoists 58 are connected by suitable couplings 108 so that movement imparted to any hoist automatically is transferred to the other hoists in the assembly.

According to the present invention, driving means is provided only for the two middle transfer devices 46 and the two outer transfer devices are driven through the coordinating mechanisms hereinabove described. Both the slides 54 and the two hoists 58 are operated pneumatically.

To this end, each of the middle transfer devices 46 is provided with a pneumatic cylinder and piston assembly, designated generally by the numeral 110, which is mounted between channels 62 with the piston acting against the transverse connecting member 64 (Figs. 2 and 3). Also, each of the middle transfer devices 46 is equipped with a second pneumatic cylinder and piston assembly, designated generally by the numeral 112, which is mounted on a suitable support 114 beside one of the hoists 58 with the piston connected to the adjacent rack 86 (Fig. 2). The piston and cylinder assemblies of fluid motors 110 and 112 are respectively controlled by three-way valves 116 and 118 operated by solenoids 120 and 122 under control of limit switches LS1, LS2, LS3, LS4 and LS5. The switches LS1, LS3 and LS4 are of the normally open type closed by their respective actuators while the switches LS2 and LS5 are of the normally closed type opened by their actuators. Switches LS1 and LS2 are carried by one of the housings 70 and are actuated upon movement of the racks 86 to their left-hand limit of movement, while switch LS3 also carried by one of the housings 70 is actuated upon movement of the racks 86 to their right-hand limit of movement. Similarly, switches LS4 and LS5 are carried by the support 56 and actuated at the left-hand and right-hand limits of movement of the slide 54.

More specifically, a pair of busses 124 and 126 energized from a suitable source of electrical energy upon closure of the line switches 128 supply the control energy for the operating relays and solenoids. A conductor 130 having limit switches LS1 and LS4, and a manually closed start switch SW, connects one terminal of the energizing coil of a relay R1 to the buss 124. The other terminal of this winding is connected through a limit switch LS5 to the other buss 126 by a conductor 132. A conductor 134 connects the buss 124 through normally open contacts *a* of the relay R1 to the same terminal of the energizing winding as does the conductor 130 in by-pass arrangement to provide a locking circuit therefor so that once the relay R1 is energized it will remain in that condition until opening of the switch LS5. One terminal of the energizing winding of the solenoid 122 is connected to the buss 124 by conductor 136 while its other terminal is connected by a conductor 138 having normally open contacts *b* of the relay R1 to the buss 126. A conductor 140 having the limit switch LS3 connects one terminal of the energizing winding of a relay R2 to the buss 124, while a conductor 142 connects the other terminal of this energizing winding to the buss 126. A conductor 144 having the limit switch LS2 connects the buss 124 through normally open contacts *a* of the relay R2 to the same terminal of the energizing winding as does the conductor 140 in by-pass arrangement to the switch LS3. A conductor 146 connects the buss 124 to the normally open contacts *b* of relay R2 to one terminal of

the energizing winding of the solenoid 120; having its other terminal connected by conductor 148 to the buss 126.

The remainder of the details of the control circuit may best be described by a description of its operation. With the racks 86 in their left-hand position and, consequently, the support 56 lowered and with the slide 54 at its left-hand position with respect to the support 56, the switches LS1, LS4 and LS5 will be closed and the switches LS2 and LS3 will be opened as shown in Fig. 7. Assuming that the line switches 128 are in closed circuit position so that the busses 124 and 126 are energized, closure of the switch SW1 will energize the relay R1 through the closed switches LS1, LS4 and LS5. Closure of the contacts *a* of relay R1 establishes a holding circuit for the relay R1 in by-pass arrangement to the switches SW, LS1 and LS4 which can now be opened without interrupting the cycle of operation about to be described. Closure of the contacts *b* of the relay R1 establishes a circuit from the buss 124 through conductor 136, the energizing winding of the solenoid 122 and the conductor 138 to the buss 126. Energization of the solenoid 122 moves the valve 118 downward thereby admitting fluid pressure to the left-hand pressure chamber of the fluid motor 112 whereby the piston 150 thereof is moved to the right causing the racks 86 to rotate the pinions 80 and 84 and drive the rack 76 in an upward direction raising the slide 54 and support 56 to cause the V-blocks 60 to lift the work from the V-blocks 52. Initial movement of the racks 86 and the connecting rod 98 in a direction toward the right acts to open the limit switch LS1 without effect since the by-pass circuit through the conductor 134 and the contacts *a* of the relay R1 is now closed and to close the switch LS2 without effect since the contacts *a* of the relay R2 are now open. As the slide 54 reaches its uppermost position due to the racks 86 reaching their rightmost position, the limit switch LS3 is closed thereby energizing the relay R2 through an obvious circuit and closing contacts *a* and *b* of this relay. Closure of contacts *a* completes a holding circuit through the conductor 144 for the energizing winding of the relay R2 since the limit switch LS3 is now closed. Closure of the contacts *b* of the relay R2 completes an obvious energizing circuit for the solenoid 120 whereby the valve 116 is moved downwardly to supply fluid pressure through the left-hand chamber of the fluid motor 110 so that the piston thereof will move toward the right moving the slide 54 relative to the support 56 in a right-hand direction, whereby the respective V-blocks 60 and the work supported thereby are transferred from one station to the next station. Upon initial movement of the slide 54 to the right, limit switch LS4 is opened without effect since the relay R1 is energized through the by-pass conductor 134. Upon completion of the stroke of the slide 54 to the right, the limit switch LS5 is opened thereby de-energizing the relay R1 permitting the contacts *a* and *b* thereof to open. The opening of the contacts *a* of the relay R1 is without effect since the circuit therethrough was broken upon opening of the limit switch LS5. Opening of the contacts *b* de-energizes the solenoid 122 so that the valve 118 may be moved upwardly by the spring 150 permitting fluid pressure to be applied to the right-hand pressure chamber of the fluid motor 112 and to permit the fluid to exhaust from the left-hand chamber thereof.

The racks 86 now move in a left-hand direction

as shown in Fig. 2 thereby lowering the support 56 and the slide 54 permitting the work carried by the V-blocks 60 to be received by the work supporting V-blocks 52. Initial movement of the racks 86 in a leftward direction opens the limit switch LS3 which opening is without effect since a by-pass circuit therearound is made through the now closed limit switch LS2 and the contacts *a* of the relay R2. Upon completion of the leftward travel of the racks 86 and consequent downward movement of the slide 54 and its support 56, the limit switch LS1 is closed without effect since the switches LS4 and LS5 are now open. The switch LS2 is opened thereby de-energizing the relay R2 causing its contacts *a* and *b* to open. Opening of the contacts *b* de-energizes the solenoid 120 permitting the spring 152 to actuate the valve 116 back to the position shown whereby fluid pressure is supplied to the right-hand pressure chamber of the fluid actuator 110 and the left-hand chamber is open to exhaust. The slide 54 now moves leftwardly with respect to the support 56 bringing the slide 54 back to its original position. In its initial movement of the slide 54 toward its original position, the switch LS5 closes without effect since switch LS4 is still open. Upon completion of the movement to the original position, switch LS4 is closed and if the manually operated switch SW1 is still closed another cycle exactly the same as the one just described will be initiated whereby additional workpieces are transferred from one station to the next station.

The apparatus shown in Figs. 10-20 is adapted primarily for transferring axle housings of automotive vehicles progressively and automatically through a series of work stations designated generally by the numerals 154, 156, 158, 160, and 162. In the form of the invention here shown, alternate stations 154, 158, and 162 are idle stations and the remaining stations 156 and 160 are occupied by machines which perform some operation on the workpiece. The machines here shown in stations 156 and 160 are conventional and comprise no part of the present invention.

In this connection, however, it will be readily apparent that the sequential relationship of the work stations is not critical; viz., the machines need not be arranged alternately with respect to the idle stations. If desired, two or more machines may occupy adjacent positions or two or more idle stations may be disposed between adjacent machines, depending upon the exigencies of the particular situation. Also, although five work stations are here shown, it will be readily apparent that the apparatus can be adapted to a greater or lesser number of stations. In each instance, the number of stations will vary, depending upon the character of the work being handled and the nature of the operations to be performed thereon. It is essential that the work stations be arranged in alignment and that they be spaced equal distances apart; however, it is contemplated that several apparatuses of the type here shown may be used side by side and in conjunction with means for transferring the workpieces from one apparatus to another if a large number of operations are to be performed on the workpiece.

Each work station is equipped with suitable stationary work supports upon which the workpiece rests, and the work supports in the various stations are all arranged at a uniform height. In the apparatus here shown, the work supports comprise spaced V-blocks 164 which engage the axle housing workpiece 166 adjacent its ends.

Two V-blocks 164 should be provided in each station but these blocks may be spaced various distances apart. For example, in the idle stations 154, 158, and 162 the V-blocks 164 are positioned to engage the axle housing immediately behind the end flanges thereof; whereas, the V-blocks in work stations 156 and 160 are positioned to engage the axle housing at the outer sides of the flanges.

Any suitable supporting structure may be provided for V-blocks 164. In idle stations 154, 158, and 162 the V-blocks 164 are mounted on generally box-shaped supports 168, and in work stations 156 and 160 the V-blocks are mounted on supporting arms 170 which are fastened on the machines in such stations. In this connection, however, it will be readily apparent that, if desired, a separate supporting structure may be provided for the V-blocks 164 in those stations occupied by machines.

In this form of the invention, the transfer device is mounted above and extends the full length of work stations 154-162. A suitable supporting framework for the device is provided, and this framework is here shown in the form of a plurality of inverted U-shaped supports 172 which straddle the line of work stations and are disposed substantially equidistantly therealong. Welded or otherwise fastened substantially centrally to the crosspieces of supports 172 is a longitudinal stringer 174. This framework can be fabricated from structural members of any suitable size or shape and the elements thereof are welded, bolted, or otherwise fastened solidly together to provide an essentially rigid structure. In the form of the invention here shown, the supports 172 are made of I beams, and the stringer 174 comprises a pair of channels arranged back to back in spaced parallel relation.

The transfer device itself is suspended from the supporting structure hereinabove described and comprises a longitudinal slide support 176 which extends across all five work stations and is suspended from the stringer 174 by a plurality of hoists 178. Carried by and depending from the slide support 176 is a slide member 180 which extends longitudinally of the apparatus across four of the five work stations and is equipped with a pair of work-holding members 182 for each of the four work stations. It will be observed that the slide 180 is adapted to travel horizontally with respect to the slide support 176 on a series of rollers 184 and that the work-holding members 182 in each pair are positioned to engage opposite ends of the workpiece 166. Also, it will be observed that the work-holding members 182 are pivotally mounted on the slide 180 and that they are movable on their pivots between the full- and broken-line positions in Fig. 16. In the broken-line position the work-holding members are closed to engage terminal portions of the workpiece 166 whereas in the full-line position the work-holding members are spaced apart or opened to disengage the workpiece.

The transfer mechanism is raised and lowered by the hoists 178. When the transfer mechanism is fully lowered, the portions of work-holding members 182 which engage the workpiece 166 are positioned below the terminal portions of the workpieces, and when the transfer mechanism is raised with the work-holding members closed, the workpieces are raised simultaneously from the stationary work supports 164. Suitable mecha-

nism is provided for operating and co-ordinating hoists 178 so that they raise and lower the slide support 176 and its appurtenances a distance sufficient to move the work-holding members 182 from a position below the terminal portions of the workpieces 166 to a position where the workpieces 166 carried by work-holding members clear the stationary work supports 164. Manifestly, if the hoists 178 are raised with the work-holding members 182 closed, the workpieces 166 are raised from the stationary work supports 164 and transposed to another station when slide 180 is moved horizontally; whereas, if the hoists are raised with the work-holding members open, the workpieces remain on stationary supports 164 and the transfer device is raised sufficiently to clear the workpiece when the slide 180 is moved horizontally. Mechanism also is provided for translating the slide 180 a distance equal to the distance between adjacent work stations, which mechanism is operable only when hoists 178 are raised but with the work-holding members 182 either opened or closed.

Initially, hoists 178 are in lowered position with the slide 180 in retracted position above the first four work stations 154, 156, 158, and 160 and with the work-holding members 182 open. In a typical cycle of operation all of the work-holding members 182 are first closed simultaneously to engage all four workpieces 166 in stations 154, 156, 158 and 160, and hoists 178 are then raised to lift the workpieces simultaneously from the above stations. When the hoists 178 are fully raised, slide 180 is actuated to move all of the workpieces 166 one station to the right, as viewed in the drawing (Figs. 10A and 10B). Hoists 178 are then lowered to deposit workpieces 166 in the adjacent stations 156, 158, 160, and 162 respectively, and the work-holding members 182 are opened to disengage the workpieces. Hoists 178 are then raised, the slide 180 retracted to its initial position, and the hoists lowered with the work-holding members 182 open to complete the cycle of operation.

Control mechanism may be provided for performing the series of operations described above automatically either continuously or periodically at fixed intervals, or, alternatively, the control mechanism may be made to operate only under the control of a manual starter switch and to perform the series of operations automatically only when the starter switch is operated.

After each cycle of operation, a new workpiece is placed either manually or automatically on the stationary work supports 164 of work station 154, and a workpiece is removed either manually or automatically from the work supports of station 162.

Each of the hoists 178 is identical in construction and operation, and a detailed description of one therefore will suffice. For this description reference is had to Figs. 11 and 12 wherein the numeral 186 designates a housing for a rack 188 and a pinion 190. The housing 186 is arranged below the stringer channels 174 and is fastened solidly thereto by bolts 192. Within the housing 186 and disposed substantially midway between the channels 174 is a vertical bore 194 which receives the rack 188, and sleeve bearings 196 are provided in opposite ends of the bore to slidably support the rack. Rack 188 extends entirely through the housing 186, and a cap 198 is fastened to the upper end thereof to limit downward movement of the rack. On the projecting lower end of rack 188 are brackets 200, which brackets are fastened to the slide carrier 176 by bolts 202 or

the like. A plate 204 interposed between brackets 200 and slide carrier 176 hold the two channels which make up the carrier in fixed spaced relation. The pinion 190 is keyed on a stub shaft 206 which is rotatably supported in the housing 186 by roller bearings 208. Packing glands 210 around the projecting terminal portions of stub shaft 206 and fastened to housing 186 by bolts 212 retain the bearings 208 and prevent lubricant in the housing from escaping along the shaft. As best shown in Fig. 11, the pinion 190 is disposed in a chamber 214 which opens exteriorly of the housing and communicates at right angles with bore 194. The pinion is inserted in housing 186 through the open outer end of chamber 214, and the latter is normally closed by a removable plate 216.

In operation, the pinion 190 is rotatably driven to raise or lower the rack 188. It will be readily apparent that actuation of the rack raises or lowers the slide carrier 176 and its appurtenances.

In order to co-ordinate the hoists 178, connecting rods 218 are inserted between the pinion shafts 206 of the various hoists and connected thereto by suitable couplings 219. Thus, rotation of the shafting 206, 218 operates the hoists 178 in unison.

In the form of the invention here shown by way of illustration, hoists 178 are operated by means of a fluid motor 220 which is mounted on the stringer 174 at substantially the middle thereof. Fluid motor 220 comprises the usual cylinder 222 and a piston (not shown) having the usual piston rod 224. The latter extends downwardly from the cylinder and carries a rack 226 which meshes with a pinion 228. Both the rack 226 and pinion 228 are mounted in a suitable housing 230 which is generally similar to the housings 186 hereinabove described. The housing 230 is disposed below and bolted to the stringer 174 in alignment with the fluid motor 220 (Fig. 19). Pinion 228 is keyed or otherwise fixed on a shaft 232 which is coupled in the shafting which operates the hoists 178 (Fig. 10A).

Manifestly, when the fluid motor 220 is operated to move piston rod 224 and rack 226 downwardly, pinion 228 drives the shafting 206, 218, and 232 in a clockwise direction, as viewed in Fig. 19, to raise hoists 178 and the work transfer device carried thereby. Alternatively, operation of the fluid motor 220 to raise piston rod 224 and rack 226 rotates the pinion 228 and the shafting associated therewith in a counterclockwise direction, as viewed in Fig. 19, to lower the hoists 178 and the work-transfer device carried by the hoists.

The slide 180 comprises a pair of channels arranged back to back and in spaced parallel relation as shown in Fig. 14 and held rigidly together by cross plates 234. As suggested, the slide 180 extends over four of the five work stations and is movable from a position above stations 154, 156, 158, and 160 to a position above stations 156, 158, 160, and 162. Cross plates 234 are provided with upstanding arms 236 (Fig. 10A) which carry the rollers 184. As suggested, sets of rollers are provided at longitudinally spaced intervals along the slide; and there are two rollers in each set, which rollers ride on the lower flanges of respective slide-supporting channels 176.

Slide 180 is actuated by a fluid motor 238 (Fig. 18) which comprises the usual cylinder 240 and a piston (not shown) having a piston rod 242.

On the distal end of the piston rod 242 is a rack 244 which operates in suitable guides 246 and actuates a second rack 248 through the medium of a small gear 250 disposed between the two racks. As clearly shown in the drawing, the fluid motor 238 and rack 244 are mounted between and carried by the two carrier channels 176, and the rack 248 is fixed to the slide 180.

When piston 242 is advanced, rack 244 is moved to the right, as viewed in Fig. 18, and pinion 250 is rotated in a clockwise direction to move rack 248 to the left. Manifestly, slide 180 will move with the rack 248. Conversely, retraction of the piston rod 242 moves rack 244 to the left, as viewed in the drawing, and rotates the pinion 250 in a counterclockwise direction to move rack 248 and its appurtenances to the right. As suggested, the stroke of piston 242 is sufficient to move the slide 180 a distance equal to the distance between adjacent work stations.

With reference to the work-holding members 182, it will be observed (Fig. 15) that the two supporting channels 180 are held in fixed relation by spacers 252 and that the channels are bolted or otherwise held solidly together. A pair of work-holding members 182 is provided for each work station covered by the slide 180, and each work-holding member is pivoted to a supporting bracket 254 which in turn is welded or otherwise secured to the slide 180. As best shown in Fig. 16, members 182 are arranged vertically on horizontal pivots and the lower ends thereof carry blocks 256 which project laterally to support a terminal of the workpiece 166. An actuator linkage connects the upper ends of each pair of work-holding members and means is provided for operating the linkage to open and close the members in the manner hereinabove described, viz., to move the work-holding members between the full- and broken-line positions in Fig. 16.

Specifically, each linkage comprises a relatively short lever 258 which is disposed between the two channels 180 and substantially midway between the two work-actuating members 182. Lever 258 is keyed or otherwise fixed on a shaft 260 which is journaled in a mounting attached to one of the channels 180. The ends of lever 258 are connected to respective work-holding members 182 by links 264, and each link is connected to its respective work-holding member by a lost-motion connection designated generally by the numeral 266.

When the shaft 260 is rotated to position lever 258 substantially horizontally, as shown by broken lines in Fig. 16, the links 264 close the holding members 182. Conversely, when shaft 260 is rotated to move the lever 258 to the position shown by full lines in Fig. 16, links 264 pull the attached ends of work-holding members 182 toward each other and rock such members about their pivots to the full- or open-line position. In the latter position, work-holding members 182 release the workpiece 166.

It may thus be seen that both work-holding members 182 in each pair are operated in synchronism and that they are opened or closed simultaneously. Also, by reason of the instant arrangement, the actuator linkage is positioned between and protected by the spaced slide channels 180. In this connection, it will be readily apparent that the strong rigid slide provides an excellent support for the work holders and the actuator mechanism and that the entire structure is compact and exceedingly strong.

According to the present invention, the pairs of

work-holding members 182 are operated together by a pneumatic actuator means. For this purpose a fluid motor 268 is bolted to a mounting plate 270 at one end of the slide 180 with the piston rod 272 disposed behind and parallel to the channel which carries the stub shafts 260. Preferably the mounting plate 270 extends beyond the motor 268, and the projecting portion thereof forms one of the spacers 252 as shown in Fig. 15. Each of the stub shafts 260 is provided with a pinion 274 and aligned racks 276 mesh with these pinions. Each rack 276 is slidably mounted in a guide assembly 278 which is welded on the adjacent channel 180, and the racks are connected to each other and to the piston rod 272 by suitable connecting rods 280.

From the foregoing it will be readily apparent that, when piston 272 is retracted, racks 276 are moved simultaneously to the left-hand limits of their travel and stub shafts 260 are rotated in a clockwise direction, as viewed in Fig. 16, to close the work-holding members 182. Conversely, advancement of piston 272 moves the racks 276 in unison to the right as viewed in Fig. 15 and rotates the stub shafts 260 in a counterclockwise direction to open the work-holding members 182. Since all of the racks 276 operate in unison, all of the pairs of work-holding members operate synchronously.

In the form of the invention here shown, each work-piece 166 is supported substantially at its middle by a holding pad 282 which is suspended from and bolted to a mounting block 284 on the slide 180. The mounting bolts 286 which hold pad 282 on the block 284 permit limited movement of the pad relative to the mounting plate, and spring means 288 interposed between the mounting and pad urge the latter downwardly against the workpiece 166. By reason of the spring-pressed engagement between pad 282 and work-piece 166 the latter is held in a selected rotatably adjusted position in the work holders 182.

The control system for the modified form of transfer apparatus shown in Figs. 10 through 20 comprises three-way valves 290, 296, and 302 for controlling the flow of pressure fluid to the fluid motors 268, 220, and 238 respectively. Each of the valves is operated by a pair of solenoids 292-294, 298-300, and 304-306 respectively. The valves 290, 296, and 302 are each of the type in which the energization of one of its controlling solenoids will actuate the valve into the respective controlling position after which the valve will remain in that position irrespective of the continued energization thereof until such time as the other of its controlling solenoids is energized. The energization of the various solenoids is controlled by a series of normally open limit switches LS-7, LS-8, LS-9, LS-10, LS-11, and LS-12 which are actuated to closed position at the end limits of travel of the various movable members.

Limit switches LS-7 and LS-8 are actuated respectively when the work-holding members are in a released and a work-holding position and are carried in fixed relation with the fluid motor 268. Limit switches LS-9 and LS-10 carried by the slide support 176 are actuated respectively upon movement of the slide 180 to its left-hand and its right-hand positions by abutments 308 and 310 carried by the rack 284. Limit switches LS-11 and LS-12, carried by the housing 186 of the hoist 178, are engaged by an abutment 312 carried by the rack 188 for actuation thereof upon downward and upward movement respectively of the work-carrying slide 180. The limit

switch LS-12 is of the double-circuit-controlling type having two independent sets of normally open contacts LS-12a and LS-12b, each being arranged to be moved to closed position upon actuation of the limit switch LS-12 by the abutment 312.

A manually operable starting switch SS-1 is moved to closed position to start the cycle of operation which comprises actuating the work-holding members or hooks 182 into work-holding position with respect to the workpiece 166, actuating the hoist 178 to lift the workpieces 156 upward, actuating the slide member 180 to move the workpieces 166 horizontally to the next station, actuating the hoists 178 to lower the workpieces 166, actuating the hooks 182 to move them out of work-holding position with respect to the workpieces 166, actuating the hoists 178 to raise the hooks 182, actuating the slide member 180 whereby it is returned to its left-hand position, and actuating the hoists 178 to lower the hooks 182 into a position in which they are in a position to be actuated for lifting the next workpiece 166. As each of the foregoing steps is completed, limit switches LS-7 through LS-12 are actuated, whereby the series of steps is carried on automatically without further effort on the part of the operator.

Power from a suitable source of supply is supplied to the bus conductors 314 and 316 through usual line switches 318 and 320 respectively. One terminal of the energizing winding of the solenoid 292 is directly connected to the bus 314 while the other terminal is connected through the start switch SS-1 and contacts *a* of a work-cycle control switch WS-1 to the bus 316. One terminal of the energizing winding of the solenoid 294 is connected directly to the bus 314 while the other terminal is connected through the contacts *b* of the switch WS-1 and through the contacts *a* of the control relay CR-7 to the line 316. Likewise, one terminal of each of the energizing coils of the solenoids 298, 300, 304, and 306 is connected to the bus conductor 314. The other terminal of the energizing winding of the solenoid 298 is connected to the bus 316 through two parallelly arranged conductors 322 and 324. The conductor 322 has therein the contacts *a* of the control relay CR-4 and the contacts *a* of the control relay CR-6. The conductor 324 contains the contacts *a* of the control relay CR-3 and the contacts *a* of the control relay CR-5. The other terminal of the energizing winding for the solenoid 300 is also connected through two parallelly extending conductors 326 and 328 to the bus conductor 316. The conductor 326 contains the normally open contacts *b* of the control relays CR-3 and CR-6 while the conductor 328 contains the normally open contacts *b* of the control relays CR-4 and CR-5. The other terminal of the energizing winding for the solenoid 304 is connected through the normally open contacts LS-12a and the normally open contacts *c* of the control relay CR-3 to the bus conductor 316. Likewise, the other terminal of the energizing winding of the solenoid 306 is connected through the normally open contacts LS-12b and contacts *c* of the control relay CR-4 to the bus conductor 316. A conductor 330 is interconnected between the bus conductors 314 and 316 and has therein the limit switch LS-11 and the control winding for the control relay CR-7. A conductor 332 is also connected between the bus conductors 314 and 316 and has therein the limit switch LS-9 and the energizing winding for the control relay CR-6.

Likewise conductors 334, 336, and 338 are also connected between the bus conductors 314 and 316 and have respectively therein the limit switch LS-10 and the energizing winding for the control relay CR-5, the limit switch LS-7 and the energizing winding for the control relay CR-3, and the limit switch LS-8 and the energizing winding for the control relay CR-4. It is believed that the remaining details of the electrical circuit for the invention as illustrated in Figs. 10 through 20 may best be understood by description of operation which is as follows:

Upon closure of the switches 318 and 320 the conductor busses 314 and 316 will be energized with electrical potential from a suitable source of supply. Since at the end of each cycle of operation the slide 180 will be lowered and in its left-hand position and the hooks 182 will be open, the limit switches LS-7, LS-9, and LS-11 will be actuated and maintain the relays CR-3, CR-6, and CR-7 energized. Energization of the relays CR-3 and CR-6 completes an energizing circuit for the solenoid 306 through the now closed contacts *b* thereof. The work cycle control switch 25 will normally be in its shown position with the contacts *b* closed so that the closure of the contacts *a* of the relay CR-7 will act to energize the solenoid 294, whereby the hooks 182 will be maintained out of work-engaging relation. If by any possible chance the hoist 178 should be elevated at the time the line switches 318 and 320 were closed, the limit switch LS-12 will be closed; and since the contacts *c* of the control relay CR-3 are also closed due to the aforesaid energization of the relay CR-3 the solenoid 306 will be energized to provide the necessary actuation for the fluid motor 238 whereby the hoist 178 is actuated to lowered position closing the limit switch LS-11 for energization of relay CR-7.

When it is desired to initiate a cycle of operation of the transfer apparatus, the work cycle control switch WS-1 is moved to its up position whereby contacts *a* thereof are closed so that when the starting switch SS-1 is closed, an obvious energizing circuit for the solenoid 292 will be closed. The switch WS-1 may be moved to its up position manually or such movement may be the consequence of some other associated function such as the completion of a machining or other work operation at the various stations. It may further be stated that the switch WS-1 is actuated to its shown or down position at some instant after the limit switch LS-11 has opened due to upward movement of the hoist 178 and before the workpiece has been completely lowered into its next position. Again this actuation of the switch WS-1 to down position may be as a consequence of the movement of the workpiece or of the transfer apparatus or may be manual, as desired.

Closure of the starting switch SS-1 establishes an obvious circuit for the solenoid 292 through the now closed contacts *a* of the switch WS-1 whereby the valve 290 is moved in an upward direction so that fluid pressure is applied to the fluid motor 268 for moving the connecting rod 272 thereof in a direction toward the left which, as stated hereinbefore, will act to close the hooks 182 against the ends of a workpiece 166. Initial movement of the fluid motor 268 to the left will cause the limit switch LS-7 to open, thereby de-energizing the control relay CR-3 and opening the contacts *a*, *b*, and *c* thereof. Opening the contacts *a* is without effect since the control relay CR-5 is now de-energized and the contacts *a*

thereof are open, breaking the circuit through the conductor 324. Opening of the contacts *b* of the control relay CR-3 de-energizes the solenoid 300, which circuit was previously completed through the conductor 326 and the closed contacts *b* of the control relay CR-6 under control of the limit switch LS-9. Opening of the contacts *c* of the control relay CR-3 is without effect since the contacts LS-12a are already in open position.

As the fluid motor completes its stroke to the left, the limit switch LS-8 will be closed, completing an obvious energizing circuit for the control winding of the relay CR-4, causing the contacts *a*, *b*, and *c* thereof to be closed. Closure of the contacts *a* completes an obvious circuit through the conductor 322 for the solenoid 298 since the contacts *a* of the control relay CR-6 are at this time closed due to the closed condition of the limit switch LS-9. Energization of the solenoid 298 moves the valve 296 to its upper position whereby fluid pressure is supplied to the fluid motor 220 for moving the piston and piston rod 224 thereof in a direction to raise the hoist 178. Closure of the contacts *b* and *c* of the control relay CR-4 is without effect since the contacts *b* of the control relay CR-5 are now open circuited due to the open-circuit condition of the limit switch LS-10 and due to the open-circuit conditions of the contacts LS-12b of the limit switch LS-12.

Initial movement of the hoist 178 in an upward direction opens the limit switch LS-11 which de-energizes the energizing winding of the control relay CR-7 causing the contacts *a* thereof to open without effect since the contacts *b* of the switch WS-1 were already in open-circuit condition as before described, maintaining the solenoid 294 de-energized. Upon completion of the movement of the hoist in an upward direction, the limit switch LS-12 will be actuated and the contacts LS-12a and LS-12b thereof moved to closed position. Closure of the contacts LS-12b is without effect, since the contacts *c* of the control relay CR-3 are now in open-circuit position. Closure of the contacts LS-12a, however, completes an obvious energizing circuit for the solenoid 304 through the now closed contacts *c* of the control relay CR-4. Energization of the solenoid 304 moves the control valve 302 in its upward position in which fluid pressure is supplied to the fluid motor 238 to move the piston and piston rod 242 thereof.

Initial movement of the rod 242 in a left-hand direction causes the limit switch LS-9 to open, thereby de-energizing the control relay CR-6 whereby the contacts *a* and *b* thereof move to open position. Opening of the contacts *a* of the relay CR-6 de-energizes the solenoid 298 without effect. Opening of the contacts *b* of the control relay CR-6 is without effect, since the circuit through the conductor 326 is already broken, due to the open-circuit condition of the contacts *b* of the relay CR-3. Upon completion of the movement of the piston rod 242 to the left, the limit switch LS-10 will be actuated and closed thereby establishing an obvious energizing circuit for the control winding of the relay CR-5 whereby the contacts *a* and *b* will be closed. Closure of the contacts *a* of the control relay CR-5 is without effect since the circuit through the conductor 324 is also broken at the contacts *a* of the control relay CR-3. Closure of the contacts CR-5b completes, however, a circuit through the conductor 328 for

15

energizing the solenoid 300, since the contacts *b* of the relay CR-4 are now in closed condition due to the closed-circuit position of the limit switch LS-7. Energization of the solenoid 300 moves the valve 296 in a downward direction to the position shown, whereby fluid pressure is supplied to the lower side of the piston to move the piston rod 224 in an upward direction to lower the hoist 178.

Initial movement of the hoist 178 in a downward direction opens the switch LS-12 whereby the contacts LS-12a and LS-12b thereof are open. Opening of the contacts LS-12b is without effect since the contacts CR-3c are already in open-circuit condition. Opening of the contacts LS-12a de-energizes the solenoid 304 since the contacts CR-4c are in closed-circuit position due to the closed condition of the limit switch LS-7. As stated with respect to the de-energization of the solenoid 298, the de-energization of the solenoid 304 is without effect upon the valve 302, except as to place it in condition for operation by the solenoid 306 as will be subsequently described. Upon completion of the downward movement of the hoist 178 the limit switch LS-11 will be closed, thereby re-establishing a circuit through the conductor 330 and re-energizing the control winding of the relay CR-7 causing the contacts 30 a thereof to move to closer position. Since the contacts *b* of the switch WS-1 are now closed, the closure of the contacts CR-7a will energize the solenoid 294 moving the valve 292 to its lower position as shown in the drawing whereby fluid pressure is supplied to the fluid motor 268 for movement of the piston rod 272 in a right-hand direction to open the hooks 182.

Initial movement of the rod 272 in a right-hand direction opens the limit switch LS-8 thereby de-energizing the control relay CR-4, whereby the contacts *a*, *b*, and *c* thereof are moved to open position. Opening of the contacts *a* is without effect, since the circuit through the conductor 322 has already been broken by the open condition of the contacts *a* of the relay CR-6. Opening of the contacts *b* of the relay CR-4 de-energizes the circuit through the conductor 328 which de-energizes the solenoid 300 without effect. However, such action does prepare the valve 296 for operation by the solenoid 298. Opening of the contacts *c* of the relay CR-4 is without effect, since the contacts LS-12a are already in open-circuit condition. Upon completion of the right-hand stroke of the fluid motor 268, the limit switch LS-7 will be closed thereby energizing the control winding of the control relay CR-3 causing the contacts *a*, *b*, and *c* thereof to close. Closure of the contacts *a* energizes the solenoid 298 through the now closed circuit of conductor 324, since the contacts *a* of relay CR-5 are closed due to the closed condition of the limit switch LS-10. The valve 296 is moved to its upward position whereby fluid pressure is supplied to the fluid motor 220 for moving the rod 224 thereof in a downward direction raising the hoist 178. Closure of the contacts *b* of the relay CR-3 is without effect, since the contacts *b* of the relay CR-6 are open, due to the open-circuit condition of the limit switch LS-9. Closure of the contacts *c* of the relay CR-3 is without effect due to the open condition of the limit switch LS-12.

Initial upward movement of the hoist 178 opens the switch LS-11 whereby the control relay CR-7

is de-energized and the contacts *a* thereof opened to de-energize the solenoid 294 without effect except to render the valve 290 ready for operation in an upward direction upon energization of the solenoid 292. Upon completion of the upward movement of the hoist 178 the limit switch LS-12 will be closed, thereby closing the contacts LS-12*a* and LS-12*b*. Closure of the contacts LS-12*a* is without effect since the limit switch LS-8 is now opened and the contacts *c* of the control relay CR-4 are now in open-circuit position. Closure of the contacts LS-12*b* completes an obvious energizing circuit for the solenoid 306, since the contacts *c* of the control relay CR-3 are now closed due to the closed condition of the limit switch LS-7. Energization of the solenoid 306 moves the valve 302 to its position as shown in the drawings, whereby fluid pressure is supplied to the fluid motor 238 for movement of the piston and rod 242 thereof in a right-hand direction to cause the slide 180 to move in a left-hand direction.

Initial movement of the slide 180 in a left-hand direction or the piston rod 242 in a right-hand direction causes the contacts LS-10 to open, thereby de-energizing the control relay CR-5. Opening of the contacts *a* of the relay CR-5 acts to de-energize the circuit through the conductor 324 and the now closed contacts *a* of the relay CR-3 thereby de-energizing the solenoid 298 without effect upon position of the valve 296. Opening of the contacts *b* of the relay CR-5 is without effect, since the contacts *b* of the relay CR-4 have previously been opened due to the opening of the limit switch LS-8. Upon completion of the stroke of the slide member 180 to the left or the stroke of piston rod 242 to the right the limit switch LS-9 will be closed thereby completing an obvious energizing circuit for the control relay CR-6 whereby the contacts *a* and *b* thereof will be moved to closed position. Closure of the contacts *a* is without effect, since the circuit through the conductor 322 is now open by the open contacts *a* of the relay CR-4 due to the open limit switch LS-8. Closure of the contacts *b* of the relay CR-6 establishes a circuit through the conductor 326 and the now closed contacts *b* of the relay CR-3 whereby the solenoid 300 is energized moving the control valve 296 to its lower position as shown in the drawing, whereby fluid pressure is supplied to the fluid motor 220 for moving the piston rod 224 thereof in an upward direction and lowering the hoist 178.

Upon initial movement of the hoist 178 in a downward direction, the limit switch LS-12 will be opened, opening the contacts LS-12*a* and LS-12*b* thereof. Opening of the contacts LS-12*a* is without effect due to the open-circuit condition of the contacts *c* of the relay CR-4 under control of the open-limit switch LS-8. Opening of the contacts LS-12*b* de-energizes the circuit for the solenoid 306 through the now closed contacts *c* of the relay CR-3 under control of the closed limit switch LS-7. De-energization of the solenoid 306 is without effect upon the position of the control valve 302. Upon completion of the movement of the hoist 178 in a downward direction the switch LS-11 is closed, thereby establishing an obvious energizing circuit for the control relay CR-7 whereby its contacts *a* are closed without effect since the work-cycle control switch WS-1 is now in its upward position and the contacts *b* thereof are open circuited. Upon completion of the before-described steps, the apparatus will stop and stay in the final position which is the

same as that initially described in which the hoist 178 is down, the slide member 180 is in its left-hand position, and the hooks 182 are in open position. To restart a transfer cycle the switch WS-1 is moved to close its contacts *a* and the start switch SS-1 closed.

It may now be seen that there is provided an automatic system in which closure of the starting switch SS-1 will initiate a complete series of operations in which the workpieces are engaged by the hooks 182, are lifted by the hoist 178, are moved to the right under control of the slide member 180, are lowered by the hoist 178, and are released by the hooks 182 at the next work station. The hoist 178 then raises the work-carrying member, moves it to the left along the slide member 180, and lowers it at the original station with the hook members 182 open ready for reception of a new workpiece.

Having thus described the invention, I claim:

1. A mechanism for transferring workpieces through a series of equispaced stations comprising work-supporting means associated with each of said stations and disposed in substantially aligned equispaced relation, pairs of pivoted work-carrying arms for said stations arranged with the pairs of arms spaced according to the spacing of said work-supporting means, each pair of arms positioned to straddle workpieces on the work-supporting means of a station and movable to engage or release the terminal portions of said workpieces, means for simultaneously actuating said arms between engaged and released positions, an elongated slide common to and carrying all of said work-carrying arms mounted to travel in a direction substantially parallel to said series of stations for moving each pair of work-carrying arms back and forth from one station to another, and a hoisting mechanism carrying said slide for moving the latter together with the work-carrying arms associated therewith vertically with respect to said work-supporting means.

2. A mechanism for transferring workpieces through a series of equispaced stations comprising work-supporting means associated with each of said stations and disposed in substantially aligned equispaced relation, pairs of work-carrying arms for said stations arranged with the pairs of arms spaced according to the spacing of said work-supporting means positioned to straddle a workpiece on said work-supporting means and provided with V blocks movable under the terminal portions of said workpieces, an elongated slide common to and carrying all of said work-carrying arms mounted to travel in a direction substantially parallel to said series of stations for moving said arms back and forth between adjacent stations, a hoisting mechanism carrying said slide for moving the latter together with the work-supporting means carried thereby vertically with respect to said work-supporting means, and spring-biased pressure pads carried by and movable with said slide engageable with the workpieces intermediate the ends thereof when the hoisting mechanism is operated to lower the slide, said pressure pads being engageable with the workpieces before the V blocks are positioned to engage under the ends of the workpieces whereby said pads press the workpieces downwardly against the V blocks when the hoisting mechanism is operated to raise the slide.

3. A mechanism for transferring workpieces through a series of stations comprising work-

supporting means associated with each of said stations and disposed in substantially aligned equispaced relation, spaced pairs of work-carrying arms positioned to pick up workpieces from said work-supporting means, each pair of arms disposed to straddle a workpiece on a support and provided on the lower ends thereof with inward projections engageable under the terminal portions of said workpieces, means for actuating the arms in each pair toward and away from each other and into and out of engagement with a workpiece, means co-ordinating said actuator means for simultaneous operation, an elongated slide common to and carrying all of said work-carrying arms mounted to travel in a direction substantially parallel to said series of stations for moving each pair of said work-carrying arms back and forth between said stations, and a hoisting mechanism carrying said slide for moving the latter together with the work-carrying arms associated therewith vertically with respect to said work-supporting means.

RALPH E. CROSS.
